US00D754514S

(12) **United States Design Patent**
Huber et al.

(10) **Patent No.:** US D754,514 S
(45) **Date of Patent:** ** Apr. 26, 2016

(54) **COMPACT MANUAL SHARPENER**

(71) Applicant: **EDGECRAFT CORPORATION**,
Avondale, PA (US)

(72) Inventors: **Thomas M. Huber**, Dover, DE (US);
Eckhard Siegler, Lichtenstein (DE);
Daniel D. Friel, Jr., Kennett Square, PA
(US); **Samuel Weiner**, Wilmington, DE
(US)

(73) Assignee: **Edgecraft Corporation**, Avondale, PA
(US)

(**) Term: **15 Years**

(21) Appl. No.: **29/538,242**

(22) Filed: **Sep. 2, 2015**

(51) **LOC (10) Cl.** 08-05
(52) **U.S. Cl.**
USPC D8/93

(57) **CLAIM**

We claim the ornamental design for a compact manual sharpener, as shown and described.

DESCRIPTION

FIG. 1 is a top/front/side isometric view of a compact manual sharpener showing our new design;

FIG. 2 is a bottom/rear/side isometric view thereof;

FIG. 3 is a right side view thereof;

FIG. 4 is a left side view thereof;

FIG. 5 is a top plan view thereof;

FIG. 6 is a bottom plan view thereof;

FIG. 7 is a rear view thereof; and,

FIG. 8 is a front view thereof.

The broken lines in FIGS. 2, 4, and 5 illustrate a portion of the design that forms no part of the claim.

1 Claim, 7 Drawing Sheets
